FRICITION BOX STRUCTURE FOR STRAIGHT
KNITTING MACHINESCharles R. Fegley, Laureldale, Pa., assignor to
Textile Machine Works, Wyomissing, Pa., a cor-
poration of Pennsylvania

Application December 22, 1950, Serial No. 202,232

12 Claims. (Cl. 66—126)

1

This invention relates to friction boxes for full-fashioned knitting machines and more particularly to boxes of the type having two sets of shoes.

The yarn carriers of ordinary full-fashioned knitting machines are fixed to carrier rods or bars which are connected for operation to friction boxes releasably and frictionally connected to reciprocating friction rods. The friction boxes are adapted to be clamped to and released from the friction rods by operating levers usually worked by hand. The friction boxes are provided with metal shoes equipped with friction leathers which are pressed toward the rods by springs when said levers are turned in a certain direction. The springs are adjusted to exert sufficient pressure to cause the friction boxes, and hence the yarn carriers, to move at the same speed as the friction rods when free to do so but to permit the boxes to slip on their rods when the yarn carrier bars are stopped by adjustable stops which determine their throw or length of travel.

Such friction box structure naturally places a good deal of wear on the leathers with consequent liability to irregular and unsatisfactory operation of the boxes. With a view to lessening these troubles, the boxes have been made longer to accommodate two sets of shoes and their leathers per box per rod, thereby reducing the unit pressure on the leathers for a given grip on the rod, at least when first installed. However, various troubles then developed in the line of obtaining and maintaining the same pressure on the different shoes and leathers of given friction boxes. These troubles have flowed in part from complexity of design and in part from difficulty in maintaining the pressure transmitting means in a position to apply an equal pressure to both sets of shoes.

It is accordingly an object of the invention to provide a friction box having two sets of friction shoes in alignment longitudinally of a friction rod and which will be reliable and uniform in action as well as mechanically simple.

A further object of the invention is to provide a friction box having two sets of friction shoes in alignment longitudinally of a friction rod with a pressure transmitting means adapted to equalize pressure applied to the two sets of shoes to frictionally connect the friction box to the friction rod.

With these and other objects in view which will become apparent from the following detailed description of the illustrative embodiment of the invention shown in the accompanying drawings, the invention resides in the novel elements, features of construction and cooperation of parts, as

2

hereinafter more particularly pointed out in the claims.

In the drawings:

Figure 1 is an end elevational view of a friction box according to the invention as it appears from the left of the machine and showing the shafts and carrier rods associated with the box in section;

Fig. 2 is a view of the parts as viewed in the direction of arrows 2—2 of Fig. 1 and turned at 90° relative to Fig. 1;

Fig. 3 is an elevational view of certain of the internal elements of the friction box of Fig. 2 and with the housing member omitted;

Fig. 4 is a sectional view taken substantially on the line 4—4 of Fig. 2, certain parts including the friction box housing being omitted;

Fig. 5 is a sectional view taken substantially on the line 5—5 of Fig. 3, looking in the direction of the arrows;

Fig. 6 is a sectional view taken substantially on the line 6—6 of Fig. 3, looking in the direction of the arrows;

Fig. 7 is a detail sectional view taken substantially on the line 7—7 of Fig. 3, looking in the direction of the arrows; and

Fig. 8 is a sectional view taken substantially along the line 8—8 of Fig. 2.

In the drawings and description, only the means necessary to a complete understanding of the invention are specifically set forth; further information as to the construction and operation of other related, usual and well known knitting machine elements, mechanisms, etc., may be found in one or more of the following publications:

1. Pamphlet entitled—Full-Fashioned Knitting Machines—published and copyrighted by the Textile Machine Works, Reading, Pennsylvania, in 1920.

2. Four catalogs entitled—The “Reading” Full-Fashioned Knitting Machine Parts Catalog—published and copyrighted by the Textile Machine Works, in 1929, 1935, 1940 and 1947, respectively.

3. Booklet entitled—The “Reading” High Production Full-Fashioned Knitting Machine—which, forming a supplement to the above noted 1940 parts catalog of the Textile Machine Works, is a publication of the Textile Machine Works, copyrighted by the latter in 1940.

4. Pamphlet entitled—Knitting Machine Lectures—published by the Wyomissing Polytechnic Institute, Wyomissing, Pennsylvania, in 1935.

In the drawings, there is shown a double friction box, that is, one arranged to operate in connection with either one of the two friction box

rods as desired. However, the improvement according to the invention is not limited to double friction boxes, the novel features according to the invention being duplicated in a double friction box and only one set being in use at a given time. In accordance with the invention, there is provided for each friction rod with which the improvement is used a yoke member having a channel shape whereby it is adapted to embrace the rod and the lower members of sets of metal shoes and friction leathers arranged longitudinally of the rod and used to apply pressure to the leathers between the shoes and the friction box rod. Said yoke member is open at the top so that it can be readily fitted around the lower shoes and its sides extend upwardly above the upper shoes of the sets sufficiently so that, upper shoes and their leathers, springs and an equalizing bridge piece may all be placed between a cam pivoted on the yoke for applying pressure to the shoes and friction leathers to clamp them against the friction box rod. Said equalizing bridge piece or member is arranged to have its mid-point under the cam and its ends resting on the high points of the springs, the equalizing piece being free to tilt to maintain equal pressure on the two springs and free to move down and up as the pressure from the cam and the springs dictates but being guided in the yoke in such manner as to prevent movement relative to the yoke.

Referring to the drawings in detail and more particularly to Figs. 1 and 2, 10 indicates the usual yarn carrier rods or bars of a full-fashioned knitting machine one of which is shown connected to and operated by a friction box 12 by means of a dog 14 on the carrier rod and a slide 16 on the friction box, the slide having a portion 18 for engaging in a recess in the dog. Slide 16 is adapted to be positioned to drive any one of several of the rods 19, being mounted to slide and be releasably held in the friction box 12 by a spring pressed detent means 17 (Fig. 1) in a well known manner. As shown, box 12 comprises a frame or housing 19 adapted to be frictionally engaged to either a high speed friction rod 20 or a slow or half-speed friction rod 22. The box 12 is provided with a member 28 which is adapted to engage stop projections 25 and 27 on rods 24 and 26, the member, stops and rods being a part of a usual shock absorber mechanism for reducing the impact of the carrier rods on their end stops when the box is engaged to the high speed friction rod 20. The shock absorber mechanism, shown in detail in the aforementioned 1947 Reading catalog, forms no part of the present invention and is not further referred to herein.

Means 30 whereby friction box 12 may be frictionally engaged to a rod such as 20 comprises a yoke or member 32 best shown in Fig. 3. Yoke 32 has a generally U-shape in end elevation to embrace rod 20 as shown in Fig. 5. The sides of yoke 32 are cut out in their mid-portions as shown in Fig. 3, leaving strap portions 34 and 35 which extend transversely of and beneath the rod as shown in Fig. 4, while the upper portions of the sides of member 32 extend across the cut-outs in the sides as shown at 36 to complete the yoke. Two lower shoes 38 and 40 and their friction leathers 42 and 44 respectively, lie between the strap portions 34 and 35. The shoes are composite units, the leather portions being fixed to the metal portions, usually by rivets, not shown. Two upper shoes 46 and 48 having friction leathers 41 and 43, respectively, are shown also, these lying on top of rod 20 and extending one after the other along the rod as in the case

of shoes 38 and 40. However, on top of the upper shoes 46 and 48 are springs 45 and 47 respectively, the springs being held in place by screws 49, as shown in Figs. 2 and 8. The shoes 38 and 46 will be seen to form a pair and the shoes 40 and 48 another pair, the pairs of shoes abutting each other on the central transverse plane of box 12. In order to support the yoke 30 and thereby the lower shoes 38 and 40, the upper portions 36 of the yoke have spacing sleeves or collars 52 fixed thereto (see Fig. 6), the collars having apertures 51 therein in which is pivotally mounted a gudgeon 50. A cam 54 is fixed to the gudgeon 50 between the collars 52 by means of a set screw 53, Fig. 5.

As best shown in Fig. 4, an equalizer member 58 is placed between the springs 45 and 47 and the cam 54. Member 58 is in the form of a bridge having an end resting on substantially the mid-point of each of springs 45 and 47 and the mid-point of the bridge lying under substantially the mid-point of gudgeon 50. It will be seen that any pressure exerted downwardly by cam 54 against member 58 and thereby against springs 45 and 47 reacts against the cam 54, gudgeon 50 and yoke 32 to exert an equal upward pressure against the lower shoes 38 and 40 through strap portions 34 and 35. The tension in strap portions 34 and 35 is equalized as between the two of them by the fact that member 58 floats freely between the cam and the springs so far as oscillatory and up-and-down movements are concerned in a manner hereinafter set forth. The two pairs of shoes therefore clamp the friction box rod 20 between them with pressure in proportion to the force exerted by hub or cam 54 against member 58. In order to permit cam 54 to apply force or pressure to member 58 and to release it, the cam has a low portion 55 blending into a flat portion 59, the flat portion of the cam acting to apply pressure to the member, as shown in Fig. 4, by engagement with a flat surface 60 on the member. The pressure between the two flat surfaces 59 and 60 caused by the reaction of springs 45 and 47 when the parts are in the position shown in Fig. 4 releasably maintains the parts in this position. It is evident therefore that cam 54 acts also both as a means to compress springs 47 when desired and also as positioning means for the cam. Whenever cam 54 is turned to the position in which low point 55 is in contact with flat 60 of bridge 58, pressure on the springs is relaxed and the box 12 can be moved relative to the friction rods as desired. To permit the hub-like cam 54 to be turned to apply pressure to the springs and shoes, it has a handle 62 thereon, shown as integral with the cam. In order that the cam 54 may not turn too far when the pressure on the shoes is to be relaxed, the handle 62 has a lug 64 thereon arranged to project laterally of the plane in which the handle moves so as to contact a shoulder 66 (Fig. 3) on the yoke 32 to thereby position the cam 54 so that low point 55 of the cam will stand approximately in contact with the flat 60 on the bridge or equalizer 58. It will be understood that the description of the details of the box 12 has up to this point been limited to the portion of the box associated with rod 20 and that identical details are also associated with the rod 22. In order that box 12 may not be accidentally attached to both rods 20 and 22 at the same time, the upper part of portion 36 of each yoke 32 has two aligned apertures 68 (Figs. 3 and 4) therein in which a pin 70 (Figs. 1 and 2) may be placed to hold the handle 62 in

the position in which the cam 54 not in use is inactive. The handle for the yoke associated with the rod 22, therefore, is in its inactive position and the pin 70 therefore is shown in Fig. 2 associated with the handle corresponding to rod 22. It will be seen further that a cotter pin 72 is used with pin 70 to prevent the pin from working out of apertures 68.

The yoke 32 is held against substantial longitudinal movement relative to the frame 19 of box 12 by engagement of the strap portions 34 and 35 of the yoke with the frame 19, as shown in Fig. 2. Further, to prevent shifting of the shoes 38, 40, 46 and 48 projections 73 are provided on the inner faces of the end portions of frame 19, the ends of the shoes lying in contact with the projections 73.

As appears in Fig. 4, member 58 has a bolt 74 in one end arranged to bear on the mid-point or high point of spring 45, this bolt being adjustable to increase or decrease the pressure of the bridge on the springs and therefore the pressure of the shoes on the rod. A further detail associated with member 58 is that the member has projections 76 at one end and projections 77 at the other, both sets of projections extending transversely of the member nearly into contact with the sides of strap portions 34 and 35 to maintain the member substantially central of the yoke 32 and therefore of the springs 45 and 47. An even more important feature related to member 58 is a means for maintaining it from working longitudinally of the friction box 12 and the yoke 32. This means comprises parallel cheeks or flanges 78 which depend from the member 58 and whose opposite faces are vertical and are spaced apart sufficiently to receive a pin 80 (Figs. 4 and 7). The pin 80 is held against movement longitudinally of yoke 32, and the pin holds the member 58 but without hindrance to pivoting movements or vertical movements of the member. For holding pin 80 against longitudinal movement, the pin is provided with grooves 82 which are adapted to be engaged by side edges 90 forming a vertical slot 84 in the yoke 32, as shown in Figs. 3 and 7. The yoke 32 has a cut out portion 86 formed as a continuation of the vertical slot 84 to facilitate the insertion of the pin 80 into the slot, see Fig. 3. With this arrangement the pin 80 is restrained from movement longitudinally of the yoke 32 and the pin in turn restrains the equalizing member 58 from longitudinal movement relative to the yoke. Further, the pin 80 acts as a guide to permit the member 58 to move vertically and also oscillate about the pin so that pressure applied to the member by the cam 54 through the springs 45 and 47 will be equally transmitted to the pairs of shoes 38-46 and 40-48, respectively.

It is to be understood that the means generally described hereinabove for frictionally connecting the friction box 12 to the friction rod 20 is duplicated for connecting the box to the friction rod 22.

Of course, the improvements specifically shown and described by which the above results are obtained, can be changed and modified in various ways without departing from the invention herein disclosed and hereinafter claimed.

What I claim is:

1. A friction box for a knitting machine comprising pairs of upper friction shoes and pairs of lower friction shoes facing each other for applying pressure to a friction rod and shoes of each pair arranged one after the other along the rod,

springs arranged to contact upper surfaces of said shoes for applying pressure thereto, and means for applying pressure to said springs and for transmitting it also to the lower ones of said shoes to clamp said rod between upper and lower sets of shoes and comprising a member channel-shaped in transverse section and which is in contact with the bottoms of the lower shoes and extends upward on both sides thereof to a level above said springs, an equalizer member resting on said springs and free to turn about an approximately central transverse axis but guided against movement longitudinally of said channel-shaped member, and a cam for pressing downward on said equalizer.

2. A friction box for a knitting machine comprising pairs of upper shoes and pairs of lower shoes facing each other for applying pressure to a friction box rod and shoes of each pair arranged one after the other along the rod, springs arranged to contact upper surfaces of said shoes for applying pressure thereto, and means for applying pressure to said springs and for transmitting it also to the lower ones of said shoes to put pressure on the rod from opposite directions and comprising a member channel-shaped in transverse section and which is in contact with the bottoms of the lower shoes and extends upward on both sides thereof to a level above said springs, a rigid equalizer resting on said springs, a cam for pressing downward on said equalizer, and means for holding said equalizer against movement longitudinally of said channel-shaped member comprising a round bolt engaging the equalizer and also the central portion of the channel-shaped member but permitting the equalizer to tilt and to move down and up.

3. A friction box for a knitting machine comprising pairs of upper and pairs of lower shoes facing each other for applying pressure to a friction box rod and shoes of each pair arranged one after the other along the rod, springs arranged to contact upper surfaces of said shoes for applying pressure thereto, and means for applying pressure to said springs and for transmitting it also to the lower faces of said shoes to put pressure on the rod from opposite directions and comprising a member channel-shaped in transverse section and which is in contact with the bottoms of the lower ones of said shoes and extends upward on both sides thereof to a level above said springs, a rigid equalizer resting on said springs, a smooth round bolt having grooves therein near its ends, said channel-shaped member having apertures therein adapted to receive said bolt and having channels whose edges engage in the grooves of the bolt to hold it from movement both transversely and longitudinally of the member, and a cam for pressing downward on said equalizer when desired.

4. A friction box for a knitting machine comprising pairs of upper shoes and pairs of lower shoes facing each other for applying pressure to a friction box rod and arranged one after the other along the rod, springs arranged to contact the surfaces of the upper ones of said shoes for applying pressure thereto, and means for applying pressure to said springs and for transmitting it also to the lower faces of said shoes to put pressure on the rod from opposite directions and comprising a member channel-shaped in cross-section and which is in contact with the bottoms of the lower ones of said shoes and which extends upward on both sides thereof to a level above

said springs, a rigid equalizer resting on said springs and having spaced flanges extending downward from its mid-portion; a smooth round bolt having grooves therein near its ends and extending between said flanges; said channel-shaped member having apertures therein adapted to receive said bolt and formed to support the bolt, and a cam for pressing downward on said equalizer when desired.

5 5. A friction box for a knitting machine comprising pairs of upper shoes and pairs of lower shoes facing each other for applying pressure to a friction box rod and arranged one after the other along the rod, springs arranged to contact the top faces of the upper ones of said shoes for applying pressure thereto and means for applying pressure to said springs and for transmitting it to the bottom faces of the lower ones of said shoes to put pressure on the rod from opposite directions and comprising a member channel-shaped in cross-section which is in contact with the bottom faces of the lower ones of said shoes and extends upward on both sides thereof to a level above said springs, a rigid equalizer resting on said springs, a smooth round bolt engaged with said equalizer to prevent movement of the equalizer longitudinally of said channel member, said channel member engaged with said bolt to prevent movement of the bolt longitudinally thereof and holding the bolt in 25 engaging position with said equalizer, and a cam for pressing downward on said equalizer when desired.

10 6. A friction box for a knitting machine comprising pairs of upper and pairs of lower shoes facing each other for applying pressure to a friction box rod and arranged one after the other along the rod, springs arranged to contact the top faces of the upper ones of said shoes for applying pressure thereto and means for applying pressure to said springs and for transmitting it to the bottom faces of the lower ones of said shoes also to put pressure on the rod from opposite directions and comprising a member channel-shaped in cross-section which is in contact with the bottom faces of the lower ones of said shoes and extends upward on both sides thereof to a level above said springs, a rigid equalizer resting on said springs, a smooth round bolt engaged with said equalizer and arranged to prevent movement of the equalizer longitudinally of said channel member, said channel-shaped member having apertures therein adapted to receive said bolt and having channels whose edges engage said bolt to hold it from movement both transversely and longitudinally of the member, said edges inclined toward each other for engagement with the bolt at points within its ends but the member having straight edges below said channels and said bolt having a length whereby it rests on said straight edges, and a cam for pressing down on said equalizer when desired.

15 7. A friction box for a knitting machine comprising two sets of metal shoes for applying pressure to a friction box rod, said sets arranged one after the other along the rod and each having an upper and a lower shoe, plate springs on top of certain of said shoes and adapted to bend upwardly intermediate their ends when free of pressure and means for applying pressure to said springs tending to straighten them and comprising a channel member which is in contact with the bottoms of certain lower ones of said shoes and extends upward on both sides thereof to a level above said springs, a lever pivotally mount-

20 5 ed in the sides of said member for creating a downward pressure impulse, a cam connected to turn with said lever, and a bridge or equalizer contacting both said springs as well as said cam and free to turn about an axis intermediate its ends and to move downward to transmit pressure to said springs but guided to maintain a predetermined position longitudinally of said channel member.

25 8. An equalizer for a friction box rigid in use but adjustable transversely of its length, having lateral projections approximately at right angles to said adjustment adapted to hold it against substantial side-wise movements in use and projections substantially parallel to the direction of said adjustment adapted to hold it against longitudinal movements in use.

30 9. In a friction box having two sets of shoes longitudinally of the box, an equalizer of a length adapting it to apply pressure to shoes of both sets and having projections extending in the direction toward said shoes in use and adapted to resist movement of the equalizer longitudinally of the box.

35 10. In a friction box having two sets of shoes longitudinally of the box, an equalizer of a length adapting it to apply pressure to shoes of both sets and a pin adapted and arranged to resist movements longitudinally of the box, said equalizer having projections engaging said pin but turnable thereon.

40 11. A friction box for a knitting machine comprising pairs of upper friction shoes and pairs of lower friction shoes facing each other for applying pressure to a friction rod and the shoes of each pair arranged one after the other along the rod, springs arranged to contact the upper shoes for applying pressure thereto, and means for applying pressure to said springs and for transmitting the pressure to said lower set of shoes to clamp said friction rod between said upper and lower sets of shoes and comprising a yoke member having a portion engaging each of said lower shoes, an equalizer member engaging said springs and having movement along the vertical center line of said yoke, said equalizer also being free to turn about a transverse axis located centrally of said yoke and a cam on said yoke for engaging the equalizer to apply pressure to said springs.

45 12. A friction box for a knitting machine comprising pairs of upper and lower friction shoes facing each other for applying pressure to a friction rod, said pairs of shoes arranged one after the other along the rod, a spring arranged to contact each of said upper shoes, a yoke member having a portion engaging each of said lower shoes, a clamp member for engaging said springs and having movement along a vertical line intermediate said portions of said yoke and pivotally about an axis transverse to said vertical line, and a cam carried in said yoke member for operating said clamp member to apply equal pressure to said springs and said upper shoes and through said portions of said yoke to said lower shoes.
